Des. 220,477
Patented Apr. 20, 1971

220,477

COMBINED BOAT, TRAILER, CAMPER AND COOKING UNIT

Morton W. Johnson, 4663 Capay Court 2,
San Jose, Calif. 95118

Filed Apr. 9, 1970, Ser. No. 22,345

Term of patent 14 years

Int. Cl. D12—10

U.S. Cl. D14—3

FIG. 1

FIG. 2

FIG. 3

FIG. 4

FIG. 1 is a top plan view of a combined boat, trailer, camper and cooking unit, showing my new design;

FIG. 2 is a side elevational view, the opposite side being substantially similar in appearance;

FIG. 3 is a front elevational view; and,

FIG. 4 is a rear elevational view.

I claim:

The ornamental design for a combined boat, trailer, camper and cooking unit, as shown and described.
